UNITED STATES PATENT OFFICE.

EMIL GOETZE, OF WALLINGFORD, CONNECTICUT, ASSIGNOR TO INTERNATIONAL SILVER CO., OF MERIDEN, CONNECTICUT, A CORPORATION OF NEW JERSEY.

DESIGN FOR A BACK FOR MIRRORS OR SIMILAR ARTICLES.

SPECIFICATION forming part of Design No. 36,413, dated July 7, 1903.

Application filed June 6, 1903. Serial No. 160,437. Term of patent 7 years.

To all whom it may concern:

Be it known that I, EMIL GOETZE, of Wallingford, in the county of New Haven and State of Connecticut, have invented and produced a new, original, and ornamental Design for a Back for a Mirror or Similar Article; and I do hereby declare the accompanying drawings to be a full, clear, and exact illustration of the same, and which said drawings constitute part of this specification, and represent, in—

Figure 1, a face view of a back for a mirror

or similar article embodying my design; Fig. 2, an edge view of the same.

I claim—

The ornamental design for a back for a mirror or similar article as shown.

In testimony whereof I have signed this specification in the presence of two subscribing witnesses.

EMIL GOETZE.
